FLUORESCENT LAMP STARTER

Charles H. Hodgkins, Fairfield, Conn., assignor to
 The Bryant Electric Company, Bridgeport,
 Conn., a corporation of Connecticut

Application February 4, 1942, Serial No. 429,461

11 Claims. (Cl. 200—122)

The present invention relates to thermal relays, and more particularly to such relays for the starting of electric discharge lamps of the fluorescent type.

Lamps of the fluorescent type are now well-known to the art and in order to operate such lamps from the customary domestic source of potential of about 115 volts, they are provided with filamentary electrodes which must first be heated to an electron-emitting temperature prior to application of a sufficiently high starting voltage across the preheated electrodes.

To obtain this sequential operation, a relay is customarily employed which first connects the filamentary electrodes of the lamp in a series heating circuit to the source, and after the electrodes have been heated to electron-emitting temperature, the relay opens this series heating circuit causing a high voltage surge from an inductance element necessarily disposed between the source and one of the electrodes of the lamp. This high voltage surge is usually sufficiently above line voltage to cause a discharge between the preheated lamp electrodes, and once started, the operating voltage of the lamp is below line voltage so that the discharge is readily sustained at the available domestic potential of 115 volts.

If for any reason the discharge is not initiated on the first operation of the relay, it continues to perform its cycle of operation until the discharge is actually struck between the electrodes and the lamp finally started. Thus there are several primary requisites for a starting relay for this purpose. It must first maintain the series heating circuit closed for a period of time sufficient to bring the filamentary lamp electrodes up to full electron-emitting temperature prior to interrupting this circuit with causation of the high voltage surge from the inductance element, otherwise the filamentary electrodes will be stripped of their electron-emitting coating by the high voltage surge. Secondly, the relay must, as above noted, continue its cyclic operation provided the lamp fails to start the first time, and its entire cycle of operation must occur as quickly as possible to start the lamp to prevent the consumer from waiting in the dark for the lamp to give illumination.

Relays of this type have heretofore had certain disadvantages resulting from their above noted requisites. One such disadvantage has been that a relay of different electrical characteristics has been required for practically each wattage fluorescent lamp because of the difference in size of

the filamentary electrodes for the various wattage lamps and the voltage that must therefore be applied. In addition, the primary requisite for repetitious operation of the starting relay is itself a distinct disadvantage under certain conditions. For example, in the case of a failed fluorescent lamp the relay has heretofore continued its cycle of operation in a vain attempt to start the lamp in the same manner as though the lamp had merely failed to start on the first few operations of the relay. This not only greatly affects the useful life of the relay itself, but causes flickering of the failed lamp, which is a source of considerable annoyance to the user.

It is accordingly an object of the present invention to provide a relay which may be employed for starting fluorescent lamps regardless of their particular wattage.

Another object of the present invention is the provision of a relay for the starting of fluorescent discharge lamps which automatically operates to effectively disconnect the lamp from the source whenever the lamp fails for any reason.

Another object of the present invention is the provision of a relay for starting fluorescent discharge lamps which may be universally employed for starting such lamps regardless of their particular wattage and wherein the relay is automatically operable to disconnect the lamp from the source of supply in the event the lamp has failed.

Another object of the present invention is the provision of a thermal relay for starting fluorescent discharge lamps which performs its sequential operation with fidelity and which is economical to manufacture.

Still further objects of the present invention will become obvious to those skilled in the art by reference to the accompanying drawings wherein:

Fig. 1 is a front elevational view of the preferred form of starting relay for fluorescent lamps and showing the container therefor in section;

Fig. 2 is a fragmentary view similar to Fig. 1, but taken at 90° to the latter;

Fig. 3 is a fragmentary sectional view taken on the line III—III of Fig. 1;

Fig. 4 is a schematic diagram of a circuit arrangement for starting and operating a fluorescent lamp and showing the normal position of the relay of the present invention before, or a second or so after, closure of the lamp energizing circuit;

Fig. 5 is a schematic illustration of the relay of Fig. 1, showing its position at the instant of

closing the series heating circuit for the filamentary electrodes of the lamp;

Fig. 6 is a schematic illustration similar to Fig. 5 but showing the position of the starting relay during normal operation of the fluorescent lamp when the latter is of a wattage ranging from 15 to 30 watts;

Fig. 7 is also a schematic illustration of the starting relay of Fig. 1, but showing the position of the relay upon failure of the discharge lamp as well as what may be a periodic position of the relay when employed with lamps of a wattage in excess of 30 watts;

Fig. 8 is a sectional view taken on the line VIII—VIII of Fig. 1;

Fig. 9 is an elevational view of the bimetallic element of the relay of Fig. 1;

Fig. 10 is an elevational view of a modification which the starting relay of the present invention may take;

Fig. 11 is a side elevational view of the modification shown in Fig. 10, and

Fig. 12 is a sectional view taken on the line XII—XII of Fig. 10.

Referring now to the drawings in detail, the starting relay of the present invention is shown generally at 5 in the several figures and is housed within a metallic or plastic casing 6 together with a radio frequency condenser 7, both of which are connected in electrical parallel to a pair of contact terminals 8 and 9 adapted to engage a socket, and secured to an insulating closure member 10.

The relay itself comprises a base 11 of suitable insulating material such as fiber, a phenolic condensation product, hard rubber, or the like, and is provided with a rectangular opening 12 therein. A substantially U-shaped heat-responsive element 13 in the form of a bimetallic member, having one leg thereof longer than the other, is secured along the longest leg to an eyelet 14, which forms a pivoted support and electrical connection for the heat-responsive element 13, with this eyelet 14 being connected to the contact terminal 8 by a metallic strap 15 and to one side of the condenser 7 by a conductor 16.

The free end of the longest leg of the U-shaped heat-responsive element 13 is provided with a suitable contact 17 normally engaging a metallic heat collector 18 in the form of a supporting strap having its angularly disposed end (Fig. 2) rigidly secured to the base 11. A high ohmic resistance heating element 19 is electrically and mechanically secured to the heat collector 18 and disposed longitudinally in juxtaposition to the longest leg of the heat-responsive element 13 between its support 14 and the bottom of the U, with its other end electrically connected to an eyelet 20 by means of a conductor 22. This eyelet 20, like the eyelet 14, passes through the base 11 of the relay and is connected by a strap or the like 23 to the contact terminal 9, and to the remaining side of the condenser 7 by a conductor 24 (Fig. 3). A contact 25 is electrically and mechanically secured by the eyelet 20 so as to be normally disposed in spaced relation to a contact 26 rigidly secured to the shortest leg of the heat-responsive element 13 so that these two contacts will engage each other as hereinafter described.

Referring now more particularly to Fig. 4, the operation of the relay 5 will be described in connection with its intended purpose of starting a fluorescent lamp 27. As shown in this figure, the lamp 27 is provided with filamentary electrodes 28 and 29 which must be heated to elec-

tron-emitting temperature prior to the initiation of a discharge between these electrodes. To this end one side of the electrode 28 is connected by a conductor 30, inductance 32, and switch 33, to one side of the domestic source of supply of approximately 115 volts, and one side of the electrode 29 is likewise connected by a conductor 34 to the other side of this source. In order to complete a series heating circuit for these electrodes 28 and 29, the remaining ends of each are connected together by the relay 5 which is secured to a suitable socket (not shown) so that the terminals 8 and 9 together with conductors 35 and 36 complete the circuit.

Upon closure of the switch 33 a series heating circuit will be thus completed through inductance 32, electrode 28, relay 5, and electrode 29 back to the source L1—L2, which may be a transformer or a domestic source of 115 volts, as is well-known in the art. Since this circuit arrangement per se is well-known, it is believed unnecessary to trace the circuit in its entirety, and consequently further description will be confined to the relay 5. The current passing through the relay 5 with the switch 33 closed will flow from the contact terminal 8 and strap 23 to the eyelet 20. Since one end of the resistance heater 19 is connected to this eyelet 20 by the conductor 22, current flows through this heater to heat collector 18, through normally closed contact 17, the upper portion of the longest leg of heat-responsive element 13, and thence through supporting eyelet 14 and strap 15 to contact terminal 9, thus subjecting the heater 19 to full line voltage.

Inasmuch as the heater 19 is disposed longitudinally of the longest leg of the heat-responsive element 13 between its pivot 14 and the base of the U, the heat generated by the application of the voltage from the source, which will be across the heater, hereinafter referred to as full line voltage, is rapidly transferred to the adjacent portion of the heat-responsive element 13. Deflection of that portion, together with the bottom of the U, occurs in the direction of the base 11 with the bottom of the U passing inwardly of the rectangular slot 12 provided for that purpose. Deflection in the direction of the base 11 will accordingly cause the shortest leg of the heat-responsive element to move away from the base until contact 25 engages contact 26, in the manner shown in Fig. 5.

This engagement of the contacts 25 and 26 occurs very rapidly, requiring only a very few seconds, with the result that a low resistance heating circuit is provided for the lamp electrodes 28 and 29, allowing them to be heated quickly to maximum electron-emitting temperature, since the heater 19 is short-circuited by the engagement of the contacts 25 and 26. Short-circuiting of the resistance heater 19 results in no further generation of heat so that the heat-responsive element 13 cools sufficiently to cause it to return to its normal position with attendant separation of the contacts 25 and 26. Separation of the latter accordingly causes a high voltage surge from the inductance element 32 which is impressed across the preheated lamp electrode 28 and 29, thus striking the arc with the relay then being in the position as shown in Fig. 6. If for any reason the discharge is not initiated on the first operation of the relay 5, the heater 19 is again immediately subjected to full line voltage, with the result that it will repeat its

cycle of operation a number of times until the discharge is initiated.

Once the lamp 27 is started, the heater 19 is then subjected only to lamp voltage, and on lower wattage lamps the size of the heater 19 and area of the heat-responsive element 13 are so designed that insufficient heat is generated at lamp voltage to materially affect the heat-responsive element 13 or to cause closure of the contacts 25 and 26 during operation of the lamp. For higher wattage lamps which necessarily require a higher lamp voltage, sufficient heat would unavoidably be generated to cause closure of the contacts 25 and 26 in the absence of provision to the contrary. Accordingly, in order to universally adapt the present relay to all commercial wattage lamps, the heat collector 18 and contact 17 are provided.

In the case of higher wattage lamps where the heater is subject to a voltage approximating line voltage during operation of the lamp, the heat generated by the heater 19 will be carried to the heat collector 18; and since the latter is disposed adjacent the upper portion of the longest leg of the U-shaped heat-responsive element 13 which is in the electrical circuit, this portion will be deflected by the heat toward the base 41, thus opening the contacts 17 and 18 before the contacts 25 and 26 can close, as shown by the position of the relay in Fig. 7. Inasmuch as this completely disconnects the heater 19 from the source, there will be a continual opening and closing of the contacts 17 and 18 as the heat-responsive element responds to heating and cooling, due to intermittent current flow through the heater 19. However, in the case of all wattage lamps, should it fail to start on the first separation of contacts 25 and 26, the heater 19 will again be subject to full line voltage with repetitious operation of the relay as above noted.

In addition to the relay of the present invention being universally adapted for all commercial wattage lamps, it is also operative to "lock-out" the discharge lamp should it fail, due to deactivation of the electrodes or similar cause. In an instance of this kind the relay 5 will perform its cycle of operation a number of times corresponding to a predetermined period of time, as before mentioned, and during each attempt to start the lamp 27, the resistance heater 19 will be subjected to full line (as distinguished from a high lamp voltage as in instances of high wattage lamps) with the heat generated thereby being accumulative. The temperature of heat collector 18 accordingly will finally reach a value that will cause a cyclic breaking and making of the heating circuit by opening and closing of the contacts 17 and 18.

During the cyclic operation, the closed circuit time is insufficient to permit heating of the lower portion of the U-shaped bimetallic element 13 to the point where contacts 25 and 26 will close. Consequently, attempted starts of the lamp will be eliminated since it will be "locked-out" due to the inability of the contacts 25 and 26 to close again, with the relay 5 remaining in the position shown in Fig. 7. The current flowing through the ballast or inductance 32 will be reduced to the value which flows through the heater 19 during the closed portion of the cycling of the heater circuit, thus preventing detrimental effect to the inductance, as well as to the relay 5 itself by overheating for a prolonged period of time.

To accomplish the operation as above noted, the heat collector 18 must be of good heat con-

ducting material, such as silver or copper, and is of such shape and proportion that it will permit a number of operations of the relay 5 before thermally "locking" the relay in an open circuit condition, as well as permitting closure of the contacts 25 and 26 in the case of higher wattage lamps before causing continual opening and closing of the contacts 17 and 18. Moreover, the thermal mass of the heat collector 18 should be such that it will cool quickly and permit quick restarting of the lamp and automatically return to its normal position upon replacement of the failed lamp with a new one.

The modification as shown in Figs. 10, 11 and 12 differs in some details from that previously described but structurally is substantially the same. In this modification, however, only the "lock-out" feature is provided and the relay is consequently not adapted for all wattage lamps. Upon the application of full line voltage to the high ohmic resistance heater 49, the generated heat will again be transmitted to the U-shaped heat-responsive element 43 with attendant deflection of the leg adjacent the heater and the bottom of the U in the direction of the base 41 and into the rectangular opening 42. Again, this will cause movement of the other leg of the U away from the base 41 until the contact 46 carried by the free end thereof engages the stationary contact 45 carried by the eyelet 40, as previously described relative to the preferred modification of Fig. 1. The heater 49 is thus short-circuited and upon cooling of the heat-responsive element 43, the contacts 45 and 46 separate to cause the high voltage surge with initiation of the discharge between the lamp electrodes.

After starting of the lamp, the heater 49 will again be subjected only to lamp voltage at which insufficient heat is generated by heater 49 to cause closure of contacts 45 and 46. Should the lamp fail to start on the first operation of the relay 5, it will continue its cyclic operation several times until the discharge is finally initiated in the lamp. In the event, however, that the lamp has failed due to deactivation of the electrodes or similar cause, the heater 49 will be subjected to full line voltage each time the contacts separate.

As in the previous embodiment, a heat collector 48 is provided which in the modification of Figs. 10, 11, and 12 partially surrounds and intimately contacts the heater 49 and is so shaped and arranged that another portion 50 is disposed in juxtaposition to the leg of the U carrying the contact 46. The heat generated by repeatedly subjecting the heater 49 to full line voltage is again accumulatively transmitted to the heat collector 48 which accordingly flows to the portion 50, causing the leg of the U-shaped bimetallic element carrying the contact 46 to be heated and to deflect toward the base 41, thus preventing closure of the contacts 45 and 46 and "locking-out" the defective lamp, thereby eliminating attempted starts with annoying lamp flicker. The current in the ballast 32 is also again reduced to that value which flows through high ohmic resistance heater 49, thus protecting the ballast against detrimental or destructive current. Upon replacement of the failed lamp, the relay 5 again returns to its normal position ready for its cyclic operation.

It thus becomes obvious to those skilled in the art that a thermal relay for starting discharge lamps of the fluorescent type is herein provided which is simple and economical to manufacture. Moreover, such relay is universally operable to

start fluorescent lamps of all commercial wattages and in addition "locks out" a failed lamp so as to eliminate annoying flicker of the lamp and needless repetitious operation of the relay. Upon replacement of the failed lamp, however, the relay automatically returns to its normal position and operation.

Although several embodiments of the present invention have been shown and described, it is to be understood that still further modifications may be made without departing from the spirit and scope of the appended claims.

I claim:

1. A thermal relay for controlling an electric circuit comprising a base, heat-responsive means carried by said base, an electric heater disposed in heat transfer relation to said heat-responsive means, means operable in response to heating of said heat-responsive means by said heater upon the application of approximately line voltage to the latter to close the circuit and short-circuit said heater, and means in heat transfer relation with said heater and said heat-responsive means for accumulating heat therein upon the application of approximately line voltage to said heater for a predetermined time and operable to prevent said heat-responsive means from causing circuit closing operation of said first-mentioned means and to cause said heat-responsive means to retain said first-mentioned means in an open circuit position.

2. A thermal relay for controlling an electric circuit comprising a base, heat-responsive means carried by said base, an electric heater disposed in heat transfer relation to said heat-responsive means, circuit-closing means normally operable in response to heating of said heat-responsive means by said heater upon the application of approximately line voltage to the latter to close the circuit and short-circuit said heater, circuit-opening means associated with said heat-responsive means and normally included in the circuit, and means in heat transfer relation with said heater and said heat-responsive means for accumulating heat therein upon the application of approximately line voltage to said heater for a predetermined time and operable to cause said heat-responsive means to operate said circuit-opening means with attendant interruption of the circuit thus preventing said heat-responsive means from operating said circuit-closing means with short-circuiting of said heater.

3. A thermal relay for starting fluorescent lamps of various wattages from a source of electrical energy comprising a base, a heat-responsive element secured to said base, an electric heater disposed adjacent said heat-responsive element for transmitting heat to the latter upon the flow of current through said heater, circuit-closing means normally operable in response to heating of said heat-responsive element by said heater upon the application of full line voltage to said lamp and to said heater, to close the circuit to said lamp and short-circuit said heater and operable to open upon starting of said lamp and cooling of said heat-responsive element; and circuit-opening means associated with said heat-responsive element and normally included in the circuit with said lamp and said heater, and operable to cyclically open and close said circuit upon continued heating of said heat-responsive element by the application of lamp voltage to said heater when such voltage approximates line voltage with higher wattage lamps, to interrupt said circuit and prevent said heat-responsive element from

operating said circuit-closing means and short-circuiting said heater.

4. A thermal relay for starting fluorescent lamps of various wattages from a source of electrical energy comprising a base, a heat-responsive element secured to said base, an electric heater disposed adjacent said heat-responsive element for transmitting heat to the latter upon the flow of current through said heater, circuit-closing means normally operable in response to heating of said heat-responsive element by said heater upon the application of full line voltage to said lamp and to said heater, to close the circuit to said lamp and short-circuit said heater and operable to open upon starting of said lamp and cooling of said heat-responsive element; circuit-opening means associated with said heat-responsive element and normally included in the circuit with said heater, and means in heat transfer relation with said heater and said heat-responsive element for accumulating heat therein upon continued application of lamp voltage to said heater when such voltage approximates line voltage with higher wattage lamps and operable to cause said heat-responsive element to operate said circuit-opening means with attendant interruption of the circuit to prevent said heat-responsive element from operating said circuit-closing means with short-circuiting of said heater.

5. A thermal relay for starting a fluorescent lamp from a source of commercial voltage comprising a base, a heat-responsive element secured to said base, an electric heater disposed adjacent said heat-responsive element for generating sufficient heat only upon the application of full line voltage thereto to cause deflection of said heat-responsive element and incapable of generating sufficient heat to materially affect said heat-responsive element at a voltage below approximately full line voltage, a pair of normally open contacts operable to engage each other and short-circuit said heater upon the initial heating of said heat-responsive element by said heater in response to the application of full line voltage thereto, and heat-collecting means in heat transfer relation with said heater for accumulating heat therein upon repeated application of full line voltage to said heater for a predetermined period of time and operable to render said heat-responsive element inoperative to close and operable to maintain said contacts in an open position.

6. A thermal relay for starting a fluorescent lamp provided with filamentary electrodes from a source of commercial voltage comprising a base, a heat-responsive element secured to said base, an electric heater disposed adjacent said heat-responsive element and connected in a series heating circuit with the filamentary electrodes of said lamp for generating sufficient heat only upon the application of full line voltage to said series circuit to cause deflection of said heat-responsive element, a pair of normally open contacts cyclically operable to engage each other and short-circuit said heater upon the initial heating of said heat-responsive element by said heater in response to the application of full line voltage thereto and to open upon cooling of said heat-responsive element until said lamp is started, and heat-collecting means in heat transfer relation with said heater for accumulating heat therein upon repeated application of full line voltage to said heater for a predetermined period of time and operable to render said heat-responsive element inoperative to close and operable to maintain said contacts in an open position.

7. A thermal relay for starting a fluorescent lamp from a source of commercial voltage comprising a base, a heat-responsive element secured to said base, an electric heater disposed adjacent said heat-responsive element for generating sufficient heat upon the application of full line voltage thereto to cause deflection of said heat-responsive element, a pair of normally open contacts operable to engage each other and short-circuit said heater upon the application of normal line voltage to said heater and initial heating of said heat-responsive element, a pair of closed contacts for normally connecting said heater to said source, and means operable upon the application of line voltage to said heater beyond a predetermined period of time to cause said pair of closed contacts to open and disconnect said heater from said source to prevent said heater from operating said heat-responsive element with attendant closure of said normally open contacts.

8. A thermal relay for starting a fluorescent lamp from a source of commercial voltage comprising a base, a heat-responsive element secured to said base, an electric heater disposed adjacent said heat-responsive element for generating sufficient heat only upon the application of approximately full line voltage thereto to cause deflection of said heat-responsive element, a pair of normally open contacts operable to engage each other and short-circuit said heater upon the initial heating of said heat-responsive element by said heater in response to the application of approximately full line voltage thereto, a pair of closed contacts for normally connecting said heater to said source, and heat-collecting means operable upon continued application of approximately line voltage to said heater beyond a predetermined period of time to heat said heat-responsive element and cause said normally closed contacts to open and disconnect said heater from said source to prevent said heater from operating said heat-responsive element with attendant closure of said normally open contacts.

9. A thermal relay for starting a fluorescent lamp comprising a base, a bimetallic element carried by said base, an electric heater disposed in juxtaposition to a portion of said bimetallic element and operable upon the initial application of approximately full line voltage thereto to cause deflection of the adjacent portion of said bimetallic element in one direction and the remaining portion thereof in another direction, a contact carried by one end of said bimetallic element and engageable by said base for closing a circuit to said lamp and for short-circuiting said heater, and a heat collector in heat transfer relation with said heater and the portion of said bimetallic element remote from said heater for accumulating heat therein upon continued application of approximately full line voltage to said heater and operable to cause deflection of the portion of said bimetallic element remote from said heater in the same direction as the portion adjacent thereto to prevent engagement of said contacts with attendant closure of said circuit and short-circuiting of said heater.

10. A thermal relay for starting a fluorescent lamp comprising a base, a U-shaped bimetallic element carried by said base, an electric heater disposed in juxtaposition to one leg of said U-shaped bimetallic element and operable upon the initial application of approximately full line voltage thereto to cause deflection of the adjacent portion of said bimetallic element in the direction of said base with attendant deflection of the leg thereof remote from said heater away from said base, a contact carried by the end of the leg of said U-shaped bimetallic element remote from said heater and engageable with a stationary contact terminal carried by said base for closing a circuit to said lamp and for short-circuiting said heater, and a heat collector in heat transfer relation with said heater and the leg of said U-shaped bimetallic element remote from said heater and accumulating heat therein upon continued application of full line voltage to said heater and operable to cause deflection of the leg of said U-shaped bimetallic element remote from said heater in the same direction as the portion adjacent thereto to prevent engagement of said contacts with attendant closure of said circuit and short-circuiting of said heater.
11. A thermal relay for starting a fluorescent lamp comprising a base, a U-shaped bimetallic element carried by said base, an electric heater disposed in juxtaposition to one leg of said U-shaped bimetallic element and operable upon the application of approximately full line voltage thereto to cause deflection of the portion of said bimetallic element in the direction of said base with attendant deflection of the leg thereof remote from said heater away from said base, a spaced contact carried by the end of the leg of said U-shaped bimetallic element remote from said heater and engageable with a stationary contact terminal carried by said base upon deflection of the leg of said U-shaped bimetallic element for closing a circuit to said lamp and for short-circuiting said heater, a contact carried by the end of the leg of said U-shaped bimetallic element adjacent said heater and normally engaging a stationary contact carried by said base, and a heat collector in heat transfer relation with said heater and the portion of said U-shaped bimetallic element carrying the normally closed contact for accumulating heat therein upon continued application of approximately full line voltage to said heater and operable to cause deflection of that portion of said U-shaped bimetallic element adjacent said heat collector to cause disengagement of the normally closed contact carried thereby from the stationary contact carried by said base to interrupt the circuit to said heater to prevent the latter from heating said U-shaped bimetallic element to a temperature sufficient to cause engagement of the spaced contact carried by the leg thereof remote from said heater with the adjacent stationary contact carried by said base with attendant closure of said circuit and short-circuiting of said heater.

CHARLES H. HODGKINS.
